ATTORNEY.

UNITED STATES PATENT OFFICE.

CHARLES A. BUKOVE, OF UTE PARK, NEW MEXICO.

VALVE-GRINDER.

1,390,879.

Specification of Letters Patent. Patented Sept. 13, 1921.

Application filed December 13, 1919. Serial No. 344,651.

To all whom it may concern:

Be it known that I, CHARLES A. BUKOVE, a citizen of the United States, residing at Ute Park, in the county of Colfax and State 5 of New Mexico, have invented new and useful Improvements in Valve-Grinders, of which the following is a specification.

This invention relates to a multiple valve grinder, and the object is to provide a device for grinding the valves of an internal combustion engine, and which shall include mechanism for rotating the several valves simultaneously, withdrawing them from their seats, and reseating them, the valves 10 being rotated during the interval prior to the reseating operation.

A further object is to provide, in a device of the type indicated, a rack bar, and means for reciprocating the same, a plurality of 15 spindles, each of the latter being designed to rotate one of the valves, the spindles carrying gear wheels meshing with the rack bar, and means for elevating the spindles at intervals, in order that the valves may be withdrawn, partly rotated, and then reseated, for 20 further grinding.

With the foregoing and other objects in view, the invention consists in the novel construction, combination and arrangement of 25 elements hereinafter described and claimed.

In the drawings,

Figure 1 is a view of the mechanism, in side elevation; Fig. 2 is an end elevation, and Fig. 3 is a detail of the gearing.

The mechanism herein described may be 30 so varied that the required number of valves may be ground at one time, but in the present instance I have shown a device designed for grinding simultaneously four valves.

The valves of an internal combustion engine are designated 10, these valves being engaged, respectively, by spindle 11, the spindles being rotated constantly and being elevated at intervals, in the manner set forth 35 below.

A rack bar 13 is suitably mounted for reciprocal movement in the frame 14, and is engaged by the respective gear wheels 15 carried by the spindles 11. The spindles also 40 carry disks 16, engaged by cams 17 on cam shafts 18, the latter having fixed thereon a gear wheel 19. Gear wheel 19 meshes with gear wheel 20, having formed thereon a beveled pinion 21 meshing with beveled pinion 55 22 rotated by the crank 23.

The rack bar is provided with an extension 25 pivoted to an arm 26 having a slot in one end thereof, the slot being engaged by a wrist pin 27 on the wheel 28. Said wheel 28 has formed thereon a beveled pinion 29 60 meshing with a beveled pinion 30 on the short shaft 31 rigidly mounting gear wheel 32, the latter meshing with gear wheel 20. By this construction the rack bar 13 is reciprocated constantly, while by reason of the 65 continuous rotation of the cam shaft, the spindles 11 are elevated and the valves being ground are likewise elevated at intervals, through the medium of the cams 17 engaging the disks 16 mounted on the spindle. 70

Compression springs for holding the valves to seat are designated 33. When the valves are forcibly elevated through the operation of the cams and springs 33 are placed under compression, the springs 34 at the lower end 75 of the spindles act to raise the valves from their seats, it being understood that the springs 33 are of greater strength.

The width of the rack is such that the gear 80 wheels engaging the rack are constantly in mesh therewith and a partial rotation is imparted to the spindles and valves when the latter are raised, so that the valves are reseated in a new position. The speed of the cam shaft is considerably less than that imparted by means of the crank.

The spindle 11 is square in cross section where it engages disk 16, and is movable upwardly through the disk, so that the spindle may be raised to permit of the removal of the 90 valve for the purpose of inspecting it and adding more compound.

What I claim is—

In a valve grinder, a spindle adapted for engagement with the valve to be ground, a 95 disk carried by said spindle, a cam shaft, a cam thereon for engaging the disk and raising the spindle, a gear wheel on said spindle, a rack bar engaging the gear wheel for rotating the latter, and means for rotating the 100 cam shaft and reciprocating the rack bar in timed relation, said spindle having a square portion and the disk having a square aperture, permitting the elevation of the spindle, at times, independently of the disk and 105 without discontinuing the drive through the gear wheel.

In testimony whereof I affix my signature.

CHARLES A. BUKOVE.
